UNITED STATES PATENT OFFICE

168,763

ACOUSTICAL CORRECTION TILE

Theodore Prisland, Hillside, Ill., assignor to The Celotex Corporation, Chicago, Ill., a corporation of Delaware

Application June 27, 1952, Serial No. 20,382

Term of patent 14 years

(Cl. D18—2)

To all whom it may concern:

Be it known that I, Theodore Prisland, a citizen of the United States, residing at Hillside, State of Illinois, have invented a new, original, and ornamental Design for an Acoustical Correction Tile, of which the following is a specification, reference being had to the accompanying drawing, forming a part hereof.

Figure 1 is a front face view of the acoustical correction tile, showing the new design; and

Figure 2 is an edge view of said acoustical correction tile.

I claim:

The ornamental design for an acoustical correction tile, as shown.

THEODORE PRISLAND.
